UNITED STATES PATENT OFFICE.

HARRY M. GEIGER, OF GRAND RAPIDS, MICHIGAN, ASSIGNOR TO THE CHAMPION CASH REGISTER COMPANY, OF SAME PLACE.

MANUAL CASH-RECODER.

SPECIFICATION forming part of Letters Patent No. 583,367, dated May 25, 1897.

Application filed July 20, 1895. Serial No. 556,639. (No model.)

To all whom it may concern:

Be it known that I, HARRY M. GEIGER, a citizen of the United States, residing in the city of Grand Rapids, in the county of Kent 5 and State of Michigan, have invented certain new and useful Improvements in Manual Cash-Recorders, of which the following is a specification.

This invention relates to certain new and 10 useful improvements in manual cash- recorders; and the invention consists in the mechanism and combinations of mechanism hereinafter described and claimed; and the objects of my invention are, first, to overcome 15 the inconvenience of readjusting the strips each time the record is taken from the machine, and also to guide the free end of the strips between a propelling-roller and a friction-roller into a suitable receptacle for receiving the same; second, to combine with 20 the mechanism for moving forward the paper a series of receptacles arranged in convenient manner, so that the operator can easily, by opening the lid, reach back into 25 the proper receptacles and take out the account of each one of the clerks by simply tearing off the strip by means of a cut-off suitably situated; third, to provide suitable mechanism for advancing all the strips at a time 30 without operating the keys, the same being done, preferably, through an opening in the lower front lid, by which construction a suitable space may be left for adding the column of figures on each strip or the space may be 35 utilized for any other purpose for which the same is desirable, such as indicating the date of each day's transactions or to separate the day's transactions into sections, &c.; fourth, to overcome as much as possible the pressure 40 necessary to be exerted upon the keys in advancing the paper; fifth, to operate the paper-supporting spools directly from the keys by means of a ratchet-wheel, a pawl, and suitable mechanism connected therewith, and, 45 sixth, to prevent the operation of any two keys at the same time and to lock each key in its downward movement until the operation of opening the drawer has been completed. These objects I accomplish by means 50 of the mechanism illustrated in the accompanying drawings, in which--

Figure 1 is a side elevation of the machine with a portion of the side of the case cut away in order to show the relationship of the keys, ratchet mechanism, and the general 55 construction of the internal parts of the machine. Fig. 2 is a plan view with the top of the machine removed; and Fig. 3 is a side view of the front part of the machine with the side of the case removed, showing the operation of the key in detail, said Fig. 3 being shown on an enlarged scale.

Similar letters and figures refer to similar parts throughout the several views.

In my invention I use a cash-drawer, which 65 is shown by W, the same being contained in a suitable case.

U shows the bottom of the framework or case, and V shows the partition or framework which supports the machinery.

Y Y show the sides of the case.

Y' shows the upper front lid, Y² shows the lower front lid, and Y³ shows a shaft-bearing for the lower front lid.

The machine is a key-machine and is provided 75 with a series of rollers, each roller adapted to be moved forward by means of the depression of a key, said roller carrying with it the paper on which the entry is made.

A represents a key-lever which is provided 80 with a slot A', which slot is placed in the upper part of the key-lever, and the slot is inclined, so as to act as a cam—that is, is made a suitable distance out of the circumference of a line drawn from the center of the shaft 85 B, said shaft being the pivotal point on the key, upon which the key-lever A has its bearing, so as to produce a forward motion to the lever C and its connections when the key-lever A is depressed.

C is a slotted lever having a bearing upon the frame by means of the shaft C², and said lever has pivoted thereto at the point D' a pawl D. The lever C is slotted, so as to permit the key-lever A to pass between its two 95 sides in its forward movement. It also supports the friction-roller C' through the shaft or shaft-bearing C². As above stated, C' represents a friction-roller which operates in the slot A' of the key-lever A. It has a bearing 100 by means of a pin or shaft in the slotted lever C.

D is a pawl having a pivotal bearing in the slotted lever C by means of the pin D', said pin D' serving to attach the pawl to the slotted lever C.

5 E is a ratchet-wheel rigid with the roller 1 and having a rotating bearing upon the shaft 1' and being engaged by the pawl D, which gives it the rotary motion, as hereinafter described.

10 When the key-lever A is depressed, the roller C', moving in the slot A', moves forward the lever C, turning upon its bearing C², pushing forward the pawl D, and turning the ratchet-wheel one notch.

15 A³ is a slot in the lower end of the key-lever A and is provided with teeth. On one side of the said slot the teeth project upward and on the other side they project downward, and they are adapted to engage with the bar 20 J when the key-lever A is depressed on its downward course, so as to prevent an upward motion of the key until the operation has been completed. After the operation is completed and the drawer opened the key may 25 be returned to normal position.

A³ is a lug on the key-lever A and is adapted to come in contact with the lug N, which lug N is rigid with the rocking beam N² by means of the bar N³.

30 A⁴ is a cam-surface upon the lower part of the key-lever A and is designed to engage with the bar J when the bar J has been swung on its bearing backward from normal position under said cam A⁴.

35 N' is a shaft upon which the rocking beam N² vibrates. The shaft N' is supported on a frame 5, and its rear end is provided with a dog or detent O. The dog or detent O is adapted to engage with the locking-plate P 40 in order to hold the cash-drawer W in normal position and has a pivotal bearing at its upper end upon the rocking beam N².

P is a locking-plate upon the back end of the drawer W, with which the locking-dog O 45 engages in order to secure the drawer locked within the case.

Q is a cam-plate suitably placed upon the drawer to engage the lug M', and when the drawer is closed the cam-plate Q raises M' to 50 the position shown in Fig. 1, and also lifts with it the gravity-weighted arm M.

R is a spring adapted to throw the drawer W out when unlocked by the raising of the dog O out of the locking-plate P.

55 S is a shaft having bearings in lugs upon the supporting-frame V, said shaft being rigidly connected with the weighted arm M and with the crank K. It is adapted to be turned by the gravity-weighted arm M and thereby 60 communicate, through the rigidly-connected arm K, a downward motion to the lever J² and a backward motion to the supporting-arms J¹ and the diamond-shaped bar J.

S' S' are lugs upon the supporting-frame V, 65 through which the shaft S has its bearings.

T are antifriction-rollers in the side of

the drawer W in order to facilitate the movement of the drawer out of and into the case.

F F are pawls adapted to engage with the ratchet-wheels E. These pawls are supported 70 upon a bar G by means of the slotted bearings F' F', said slotted bearings F' F' being rigid with the bar G and forming pivotal supports for the pawls F F. The bar G is supported by rigid connections with the shaft 1' 75 by means of the supporting-arms G', said arms G' being crank-arms rigidly connected, as above stated, to the shaft 1'.

H is a lever made rigid with shaft 1' and adapted to turn said shaft, so as to give motion to the crank-arms G' G'.

L L are springs which support the key-levers A in normal position.

The rollers 1 1, &c., are rigid with the ratchet-wheels E E and are adapted to rotate on the shaft 1', they receiving their rotary motion from the pawl D through the rigid connecting ratchet-wheel E and by said motion advancing the paper, as described. The shaft 1' supports the rollers 1 1 and also 90 acts as a bearing upon which the rollers 1 1 rotate, and also supports rigidly the lever H and the crank-arms G' G'.

2 2 are friction-rollers supported on the springs 2' 2', which springs hold the friction-rollers in contact with the rollers 1 1 and clasp the paper between said rollers 1 1 and said friction-rollers 2 2.

3 is a supporting-plate over which the strips of paper or writing material are carried in their movement to the position between rollers 1 1 and friction-rollers 2 2.

4 is a bar supporting the springs 2' 2', and the same also acts as a binding-bar for the frames 5 5 and as a supporting-frame for the 105 bearings of the slotted lever C.

5 5 are frames upon which the shaft 1' has its bearings, said frames 5 5 being supported by the frame V.

6 6 are supporting slotted lugs adapted to 110 support the shafts 9 9, and also to form bearings for the supply-roll 7, 7 being a supply-roll of suitable material upon which the written statements or entries can be made. It has its bearings at the bottom of the slotted 115 lever C.

8 8 are gravity-weights having suitable lugs at each end to guide them through the slot on the supporting-lugs 6 6, thereby allowing them to act as a suitable brake in order to 120 keep the supply-rolls 7 7 in their proper position, the same bearing against the supply-rolls, so as to prevent the supply-rolls from unwinding too fast in operation.

9 9 are the supporting-shafts for the supply-rolls 7 7.

10 is a supporting-bar for the sockets 11 11 of the springs L L and having their rigid supports in frames 5 5.

11 11 are socket-bearings for the springs L L and are connected rigidly as a part of the supporting-bar 10.

12 is a spring holding the rocking beam N² in its normal position and adapted to return the same to normal position after the same has been depressed.

5 13 are partitions on a direct line with the ratchet-wheels E, so as to form suitable sides for the reception of the writing material, which is advanced between the rollers 1 1 and the friction-rollers 2 2.

10 14 is a shield inclosing the rear parts of the machine, and 15 is a shield on the inside of the case designed to hide the back of the case.

15 16 is a shield suitably slotted to admit of making records upon the writing material, and it also acts to retain the writing material in its proper place.

The operation of my invention is as follows: First, I take a supply-roll of any suitable material to be written upon and place its 20 shaft-bearings in their proper slots. Then after having placed the gravity-weight over the supply-roll to perform the function above described I take the free end of the writing material, draw it over the paper-supporting 25 table, and pass the free end between the roller 1 and the lower friction-roller 2. The friction-roller 2 presses the paper against the roller 1, so that the rotating movement of the roller 1 will turn the free end of the paper 30 between the two rollers into the back of the machine in its proper receptacle. After I have advanced the paper between the two rollers I then depress the key-lever. When the key-lever is depressed, the diamond-shaped bar J is moved backward by the cam-surface 35 on the lower tooth in the slot A² of the key-lever, so that the diamond-shaped bar passes under the cam-surface A⁴ of all of the unoperated keys, and as the depressed 40 key is pressed downward it engages with the teeth on the front side of said slot. At the same time the lug A³ engages with the lug N and depresses the other end of the rocking beam N², thereby raising the back end of the 45 rocking beam and raising the locking-dog O out of engagement with a suitable opening in the cam P. When the locking-dog O is raised out of engagement with cam P, the spring R is then allowed to operate against the drawer 50 W and throw the same out of the case, allowing the operator to make the desired change or to deposit the money received. When the key A is depressed, the rear side of the slot A' in its downward course presses against 55 the friction-roller C' and advances forward the rocking lever C, and through the rocking lever C advances the pawl D. The pawl D then turns the ratchet-wheel E, being rigidly connected with the roller 1, and the roller 60 1, having suitable strips of paper between it and the friction-roller 2, with sufficient tension to advance said strip the required distance into its proper receptacle. After the key A has completed its downward motion 65 and opened the drawer and the spring R advances out of the case the lug M' passes down the inclined surface of the cam Q, thereby al-

lowing the gravity-weighted lever M to drop from its normal position and through the shaft S communicating motion to the crank-arm K through its rigid connection, thereby bringing in engagement on its downward movement the crank-arm K with the lever-arm J², which, being rigidly connected with the bell-crank arms J¹ J⁴, then throws the diamond-shaped bar J out of engagement with the teeth in the front end of the slot A², thereby allowing the depressed lever A to return to normal position, and the same cannot be again depressed until its operation has been completed and it has returned to normal position. During its operation the diamond-shaped bar remains under the cam-surface A⁴ on all of the other keys not operated, thereby preventing them from being depressed during the operation of the depressed key. When it is desired to advance all of the operating-slips together after they have been used for a day's operation, the lever H is depressed from its normal position, thereby communicating this downward motion to the supporting-levers G' G' and through them to the bar G, through the bar G to the pawls F F, which, being in engagement with the teeth of the ratchet-wheels E E, moves them upon their 95 bearings A', and through their rigid connection with 1' advancing the paper a suitable distance to provide blank spaces to add the column of figures previously placed upon the slips or to furnish blank spaces for any entries 100 that may be required. If desired to take the strips out of the machine, the operator raises the upper front lid Y', and after having advanced the strips by means of the lever H a suitable distance he then takes these strips 105 which have been advanced into suitable receptacles and draws the strips out of the machine over the shield 14, at the lower end of which is provided a serrated steel cutter to serrate the strips, and by a sharp pull the 110 strips are severed at the desired point.

Having thus described my invention, what I claim to have invented, and desire to secure by Letters Patent, is—

1. In combination with a plurality of paper-advancing rolls, a plurality of friction-rollers adapted to retain the paper in contact with the paper-advancing rolls, and a connection adapted to operate simultaneously the series of paper-advancing rolls, substantially as described. 115
2. In combination with a plurality of paper-advancing rolls, and a plurality of friction-rolls, each roll adapted to retain the paper in contact with its corresponding advancing 120 roll, a key-lever and mechanism connecting said key-lever to said paper-advancing rolls, whereby each advancing roll is operated directly from the depression of its corresponding key and a connection adapted to operate 125 all the paper-advancing rolls simultaneously, substantially as described. 130
3. In combination with a paper-supply roll, a plurality of paper-advancing rolls, a plural-

ity of friction-rolls adapted to retain the paper in contact with its corresponding paper-advancing roll, lever mechanism for operating said paper-advancing rolls separately or simultaneously, and a series of receptacles, each receptacle adapted to receive the paper as it comes from its corresponding advancing paper-roll, substantially as described.

In witness whereof I have hereunto set my hand and seal in the presence of two witnesses.

HARRY M. GEIGER. [L. S.]
